UNITED STATES PATENT OFFICE.

AUGUSTE L. SALTZMAN, OF EAST ORANGE, NEW JERSEY, ASSIGNOR TO HARRY RUSSELL BRAND, OF NEW YORK, N. Y.

INSERT HOLDER FOR COMMODITY CONTROL DEVICES.

Application filed February 12, 1921. Serial No. 444,502.

This invention pertains to check and paper holders for use in connection with commodity control devices, being applicable to any and all uses, and in any and all machines of such general character.

The present invention has, for its object, amongst others, to provide means for carrying a card or the like, adapted to receive impressions thereupon or designations there-through or thereinto, whose physical properties are such as to render it unsuitable in certain aspects for coaction with other means in functional performances.

A further object of the invention, is, to provide means for definite registration between the carrier or holder and its contained material, and also with coacting mechanisms for successive performances or for the recognition of performances, or records previously made thereon.

Another object of the invention is to provide means of identification of the holder and to utilize these means in cooperation with suitable means in the machines with which it is used, to make an identifying record each time the carrier is used as an actuator.

The present invention is designed more particularly for use as a holder or protecting frame for an insert of paper or other material, as well as to provide substantial means for operating mechanisms, certain functions of which perform on the insert; to provide means to cooperate with these actuated mechanisms for detachably maintaining the holder in the machine for a desired period of operations, to provide a permanent article for use both for successive operations with and on the same insert or for a like purpose with successive inserts and to carry identifying means to be used, when desired, in recording each time the holder performs its actuating function. It is designed for use in connection with the insert so as to obviate all liability of inaccuracies or failure to properly function as is liable to happen if the paper or the like is used separately owing to the tendency of such materials to buckle and crease.

The device with its insert is designed pri-

marily for use in connection with recording and totalizing mechanisms and allied appliances, and to combine in the one device the function of check holder and actuator for the mechanisms with which it is used. 55

The holder serves also in lieu of a key, as has heretofore been proposed for the purpose of actuating a mechanism and for recording the identity of such an appliance, and enables one to clearly dispense with the 60 employment of such key. A machine of such general character is described and illustrated in the copending application of H. R. Brand, Serial Number 283,817, filed Feb. 29, 1919. 65

As a particular example of use or adaptation, the invention is intended as a frame for a guest check in a restaurant, on which check is listed the commodity orders and the itemized prices therefor, and which check is 70 variously handled during the time it serves its purpose.

The invention has for its further object to provide simple and efficient means for centering the check or paper to keep it in 75 proper alignment and to detachably lock the insert in such aligned position; provision also being made to facilitate the entry of the paper into the holder, and to insure the presentation of the holder in proper position to 80 the machine which it actuates and with which it cooperates.

Other objects and advantages of the invention will hereinafter appear and the novel features thereof will be particularly 85 pointed out in the appended claims.

The invention is capable of embodiment in a variety of forms, some of the most efficient of which only I have chosen to herein illustrate. 90

Referring to the drawings in which such forms are shown—

Figure 1 is a top plan view of my improved check holder.

Figure 2 is the enlarged transverse section 95 through the same as on the line 2—2 of Figure 1.

Figure 3 is a transverse section as on the line 3—3 of Figure 1.

Figure 4 is an end view. 100

Figure 5 is a side elevation.

Figure 6 is a perspective view showing the paper partially inserted in the holder.

Figure 7 is a transverse section showing a modified form.

Figure 8 is a plan view of the form shown in Figure 7 with portions broken away.

Figure 9 is a section on the line 9—9 of Figure 8.

10 Figure 10 is a sectional detail on the line 10—10 of Figure 1 on an enlargement scale.

Like numerals of reference indicate like parts throughout several views.

Referring to the details of the drawing, 15 the holder 1^a in the form shown in Figures 1 and 2 consists of an upper plate 1 and a lower plate 2, disposed in parallelism with a slight space 8 between them and spaced at opposite edges by suitable strips 3 and 4, the 20 upper and lower plates and the spacing strips being united by suitable means such as rivets or the like 5 as seen in Figures 1 and 2. This forms a unitary structure and constitutes what may be termed a skeleton 25 frame or holder having the openings 6 and 6^a in the respective plates 1 and 2 through which the check or other paper is to be displayed when in use.

The holder is closed at one end by suitable 30 means such as an intermediate strip 7 preferably of substantially the same thickness as the strips 3 and 4, and thus preserving the space 8. This space at the closed end has therein a projection 9, preferably part 35 of the strip 7, and which is shown as having inclined faces to cooperate with a similarly shaped notch 10 in the end of an insert or check 11, which is carried in the space 8, see Figure 6. This serves as an abutment for 40 the insert 11 and also acts to center the check as it is placed in position and to keep the latter in proper alignment.

The holder thus formed is provided along 45 one edge with the multiplicity of perforations 12, see Figures 1 and 6, which perforations are preferably equally spaced apart and extend through both the upper and lower plates for a purpose which will be hereinafter described, and as will be readily 50 understood in reference to Figure 2.

As a means of compelling the proper presentation of the holder to the machine with 55 which it is used, as hereinafter described; and in order to strengthen the holder which it is designed to construct of sufficiently light and thin material, such, for instance, as sheet metal or it may be sufficiently rigid celluloid or indurated fibre or the like, I 60 form the lower plate with longitudinal bulges 13, as seen clearly in Figure 2, the perforations to extend through the coincident bulge as is also clearly illustrated in Figure 2. This latter feature is deemed important, as the bulge not only serves the 65 functions hereinbefore mentioned, but it also

provides for clearance of the material either removed upset from the insert or check when it is operated upon by the punches or equivalent devices in the machine in which it is used.

The longitudinally disposed ridges 13 on either side reach of the frame are of different sizes, as appears from Figs. 1 and 2, so as to cooperate with similarly shaped parts in the cooperating machine, and will always insure the correct positioning of the holder in the cooperating machine.

The holder may be satisfactorily formed of a single piece of material and such form of holder is illustrated in Figures 7 and 8. 80 The upper and lower members 14 and 15 are formed integral, the material of which they are constructed being bent as at 16 and 17 upon opposite edges and a space 18 being provided therebetween for the reception of 85 the insert or check. In this form the bulges 19 and 20 are present and the perforations 21 are formed in the upper member 14 and in the coincident lower bulge. The central openings 22 and 22^a similar to the openings 6 and 6^a in the form shown in Figures 1 and 2 is also provided, and in order to unite the edges of the material upon opposite ends of this opening, I provided the uniting strip 23 which may be affixed to the adjacent or 95 abutting edges of the material in any suitable way so as to hold them in position and insure sufficient rigidity to the holder.

As seen in Figures 5 and 9, the entrance 100 to the opening 8 may have one face flared, as seen at 24 to facilitate the entry of the insert or check.

In order to further facilitate the proper entry and guidance of the insert or check the end wall of the opening in the holder, adjacent to the closed end may be inclined relatively to the sides of the holder, as seen at 25 in Figs 1, 6 and 8.

When the holder is constructed of a single piece, as shown in Figures 7, 8 and 9, the metal at one end is folded in to form the abutting end and the projection, as seen at 26 in Figures 8 and 9 to center the insert or check when it is inserted.

Preferably at or near the closed end of the holder there is provided a suitably shaped opening 27, see Figs. 1 and 3, adapted to cooperate with the machines hereinbefore referred to, which means detachably maintain the holder in a position during the functioning of the said machines and for desired operations on the carried insert.

At the opposite end of the holder is provided a spring locking pawl 28 which may be formed by stamping out from the material of which the holder is formed, the same being designed to detachably lock the insert in place, it being understood that the pawl or projection or prong is preferably designed for cooperation with an opening or 130

depression 29 in the lower member of the holder, as will be readily understood in reference to Figure 8, it being understood that the insert may either be punctured by the 5 prong 28 or carried in close engagement with the depression 29.

In use the check or paper is inserted through the opening in the holder, being guided at its opposite edges by the spacing 10 strips 3 and 4 or by flanges of the upper and lower members of the holder, the one edge of the paper or check being disposed in substantial alignment with and between the openings or perforations in the upper and 15 lower members of the holder as will be readily understood in reference to Figures 1 and 6. Thus positioned, the insert or check is in position to be printed upon and also to be perforated by punches or other perforating means employed in the machine in connection with which the present device is 20 designed for use, when the holder has actuated the said machine. By reason of the perforations being extended through the lower 25 member of the holder the pieces of paper removed from the check or the upset portions when punctured are automatically taken care of so that they will not interfere with the ready removal of the check after the 30 same has been perforated.

The insert is designed as a check for use in the restaurant industry and may have thereon any desired arrangement of printing or other indicia.

35 In order to further facilitate the insertion of the check or paper, I may round or bevel the entrance edges of the edge spacing means 3 and 4, as seen at 30 in Figure 1.

As will be seen upon reference to Figures 40 1 and 5, the edge spacing strips 3 and 4 terminate at a distance from the closed end of the holder providing lateral outlets 31 at one or both sides of the holder at this point in order to provide for clearance of any dust or 45 other extraneous matter that might perchance accumulate within the space between the upper and lower members of the holder, and thus interfere with the desired positioning of the insert 8^a within the holder 1^a.

50 Upon reference to Figure 2, it will be noted that the bulges at the opposite sides of the holder are of unequal widths and are arranged at different distances from the adjacent edges of the holder, that is, the bulge 55 at one edge is at a greater distance from this outer edge of the holder than is the other from its adjacent outer edge, these two features being for a purpose of insuring the proper entry of the holder into a suitably 60 shaped opening in the machines with which it is used. The holder thus formed cannot be erroneously or incorrectly entered into such an opening, and if an attempt be made to enter the holder wrong-end foremost, or 65 bottomside up, even in the dark, it will be

at once made evident that the holder is not in its proper position with relation to such opening.

At the closed end of the holder and preferably in the recess 32 therein, I have arranged type or other suitable marking means 33, as seen in Figure 1 so as to give a recording impression to register each operation of the holder upon a tape or other element disposed in the machine or device 75 with which the holder is designed for use.

Thus, for example, when the holder is in the possession of a particular person, as a salesman or a waiter for example, the type or other marking means 33 may identify the 80 particular salesman or waiter, and will thus make a record within the cooperating device of all the sales or transactions of the salesman, waiter, or other person.

The foregoing are given merely as examples of some of the most efficient ways of constructing my holder, but merely by way of illustration, for it is evident that the invention, as hereinbefore set forth, is subject to changes, variations and modifications in 90 detail, proportion of parts, etc., without departing from the invention or sacrificing any of its advantages, I therefore do not intend to restrict myself to the particular construction hereinbefore described, but reserve the 95 right to make such changes, variations and modifications as come properly within the scope of the protection prayed.

What is claimed as new is—

1. A holder for the purpose described, the 100 same having means for receiving and holding an insert, means for centralizing the insert provisions to prevent improper presentation of the insert, and means permitting the passage of means to contact with such 105 insert.

2. A holder for the purpose described, comprising upper and lower members with an intervening space and a central opening for the display of an insert and one of said 110 members having projecting portions to insure proper presentation of the holder to the device with which it is to be used.

3. A holder for the purpose described, comprising upper and lower members with 115 a space therebetween to receive an insert, one of said members being provided with outward projections to insure proper presentation of the holder to the device with which it is to be used.

4. A holder for the purpose described, comprising upper and lower members with a space therebetween to receive an insert, one of said members being provided with outward projections to insure proper presentation of the holder to the device with 125 which it is to be used, the upper and lower members being provided at one marginal edge with perforations extended through said projection. 130

5. A holder for the purpose described, comprising separated portions to receive an insert and with an opening for the display of such insert, said holder being provided at one edge with openings for the passage of means to act upon the insert, and at one end with designating means.

6. A holder for the purpose described, comprising separate portions to receive an insert and with an opening for the display of such insert, said holder being provided at one edge with openings for the passage of means to act upon the insert, and at one end with designating means, the holder being open at one end with the entrance flared.

7. A holder for the purpose described, comprising separate portions to receive an insert and with an opening for the display of such insert, said holder being provided at one edge with openings for the passage of means to act upon the insert, and at one end with designating means, the holder being open at one end with the entrance flared and with the adjacent end walls of the side guides for the insert outwardly flared.

8. A holder for the purpose described, comprising spaced-apart marginal members with an opening for the display of an insert, said holder being provided at opposite edges with outward bulges and with perforations along one edge, said perforations extending through the upper wall and through the lower wall and the adjacent bulge to provide clearance for the portions removed from an insert position within said holder.

9. A holder for the purpose described, comprising means for holding and positioning an insert so that the holder and insert may be presented together in predetermined relation to the cooperating device, said holder having means for insuring proper positional presentation of the holder and its insert to the cooperating device, and means adapted to record each operative coaction of the holding means and in the cooperating machine.

10. A holder for the purpose described, comprising means including a rigid frame for holding and positioning an insert so that the holder and insert may be presented together in predetermined relation to the cooperating device, said holder having means for insuring identical successive positional presentations of the holder and its insert to the cooperating device, and marking means on the holder for recording a transaction in the cooperating machine.

11. A holder for the purpose described comprising an open frame having means for

receiving and definitely positioning an insert adapted to receive from a cooperating machine into which the holder is inserted a record of transactions, means upon the frame for insuring its recurrent insertion into said cooperating machine always in the same position relatively thereto, and marking means on the holder for recording a transaction in the cooperating machine.

12. A holder for the purpose described, comprising an open frame having means for receiving and definitely positioning an insert adapted to receive from a cooperating machine into which the holder is inserted a record of transactions, means upon the frame for insuring its recurrent insertion into said cooperating machine always in the same position relatively thereto, and means on the holder cooperating with locking devices in said cooperating machine for preventing withdrawal of the holder during the coaction of the holder and machine.

13. A holder for the purpose described comprising a free, detached frame having means for receiving an insertible and withdrawable insert, and means for positioning and aligning the holder with its insert into a cooperating machine in a predetermined relation to the mechanism of said cooperating machine, the frame having means for preventing the insertion into the cooperating machine except in said predetermined proper position.

14. A holder for the purpose described, comprising a free, detached frame for receiving, holding and positioning an insertible and withdrawable insert so that the holder and insert may be presented together in predetermined relation to the cooperating device, said holder having means for insuring identical successive positional presentations of the holder and its insert to the cooperating device with successive inserts.

15. A holder for the purpose described comprising an open frame comprising a free, detached frame for receiving and definitely positioning an insertible and withdrawable insert adapted to receive impressions from a cooperating machine having guideways into which the holder is inserted to record transactions on the insert, and means upon the frame for cooperating with the guideways for insuring its recurrent insertion with successive inserts into said cooperating machine always in the same position relatively thereto.

In testimony whereof I affix my signature.

AUGUSTE L. SALTMAN.
